UNITED STATES PATENT OFFICE.

RICHARD L. HARDIN, OF CHICAGO, ILLINOIS, ASSIGNOR OF ONE-HALF TO
RICHARD H. HARPER, OF SAME PLACE.

WALL-PROTECTOR.

SPECIFICATION forming part of Letters Patent No. 624,796, dated May 9, 1899.

Application filed November 12, 1898. Serial No. 696,250. (No model.)

To all whom it may concern:

Be it known that I, RICHARD L. HARDIN, of Chicago, in the county of Cook and State of Illinois, have invented a new and Improved 5 Wall-Protector, of which the following is a full, clear, and exact description.

The object of the invention is to provide a device capable of convenient manipulation with one hand and especially adapted to prevent soiling wall decorations when cleaning windows, door-frames, or base-boards.

A further object of the invention is to so construct the device that it may be held against the woodwork and bear against the 15 wall without injury to either and be held in proper position with one hand while the other hand is employed in cleaning.

Another object of the invention is to so shape the device in cross-section that it will 20 incline toward the woodwork to be cleaned, engaging at its depressed edge with both the woodwork and the wall adjacent thereto, effectually preventing fluids from working between the device and the wall.

25 The invention consists in the novel construction and combination of the several parts, as will be hereinafter fully set forth, and pointed out in the claims.

Reference is to be had to the accompanying 30 drawings, forming a part of this specification, in which similar characters of reference indicate corresponding parts in both figures.

Figure 1 is a perspective view of a portion of a window-frame and a portion of the wall, 35 to which the frame is secured, also a perspective view of the improved device in position upon the wall; and Fig. 2 is a horizontal section through the wall and the window-frame shown in Fig. 1, the device being in 40 plan view and in position.

A represents a window-frame, B the wall to which the frame is attached, and C represents the body portion of the improved wall-protector. The said body portion of the protector is preferably made from a single piece 45 of metal or other waterproof material, and the said body comprises a front plate or blade 10 and a flange 11 at the outer longitudinal edge of the front plate or blade, and said flange extends from the under face of the 50 plate or blade at a right angle thereto. The

rear longitudinal edge of the flange 11 is made to taper in opposite directions from the center, as shown particularly in Fig. 1, and at the central portion of the flange a cushion 12 is 55 secured in any suitable or approved manner.

A handle 13 is provided for the body C of the device, the handle being placed about centrally between the ends of the body and adjacent to the flange 11, over and beyond which 60 the handle extends. The handle 13 may be made of the same material as the body of the device or of a different material; but preferably the handle is of a non-yielding substance, and the handle is bent or so formed 65 that its outer face is convexed and its inner face concaved, while a curved flange 14 is formed at the outer longitudinal edge of the handle. A handle so formed may be readily taken in the hand, the fingers of said hand entering the concaved portion of the handle, while the palm of the hand engages with its convexed face.

In operation the cushion 12 is made to bear against the wall, while the inner longitudinal 75 edge of the blade of the body is carried against the window-casing and rests upon the wall. Thus it will be observed that the blade-section of the body when the device is in use is given an inclination in direction of the 80 woodwork to be cleaned, so that fluid cannot flow back of the device, and it is furthermore evident that the device may be held by one hand against the wall and in engagement with the woodwork to be cleaned, leaving the other 85 hand free for cleaning purposes. It is furthermore obvious that no matter how delicate the color of the wall, it will not in the least be discolored or soiled while the woodwork is being cleaned, since the device can be moved 90 along the edge of the woodwork in any direction necessary to preserve and cover the wall adjacent to that portion of the woodwork that is undergoing the process of cleaning.

It will be evident that the inclination or 95 taper of the flange of the protector in opposite directions from its center enables the device to be readily adapted to surfaces to which it could not be conveniently applied were the flange of uniform width throughout.

100 It is further evident that any means may be provided for hanging up the device when

it is not in use—as, for example, an aperture 15 may be made at one end to receive a cord or wire.

Having thus described my invention, I 5 claim as new and desire to secure by Letters Patent—

1. A wall-protector, comprising a blade or plate, a flange extended along the outer longitudinal edge of the blade or plate and tapered in opposite directions from its center, and a handle on said blade or plate, substantially as specified.

2. A wall-protector consisting of a body, which body comprises a front or main plate

and a flange at the outer longitudinal edge of 15 said main plate, said flange being tapered in opposite directions from its center, a cushion located at the central portion of the inclined edge of the flange, and a handle attached to the body at its flanged edge, which handle is 20 curved over and beyond the flange, the inner face of the handle being concaved and its outer face convexed, as described.
